UNITED STATES PATENT OFFICE.

ROBERT B. LEEPER, OF DENVER, COLORADO, DEDICATED, BY MESNE ASSIGNMENTS, TO
THE CITIZENS OF THE UNITED STATES OF AMERICA.

MEANS FOR REMOVING HAIR AND SCURF FROM HOG CARCASSES.

Application filed July 13, 1923. Serial No. 651,417.

(FILED UNDER THE ACT OF MARCH 3, 1883, 22 STAT. L., 625.)

To all whom it may concern:

Be it known that I, ROBERT B. LEEPER, a citizen of the United States of America, and an employee of the United States Department of Agriculture, residing at Denver, in the county of Denver, State of Colorado, have invented a new and useful Means for Removing Hair and Scurf from Hog Carcasses, of which the following is a full, clear, and exact description.

This application is made under the act of March 3, 1883, chapter 143 (22 Stat. 625) and the invention herein described and claimed may be used by the Government of the United States or any of its officers or employees in the prosecution of work for the Government, or by any citizen of the United States, without payment to me of any royalty thereon.

The object of the invention is to provide a comparatively inexpensive device, simple in construction and susceptible of advantageous employment, and providing means by which hair and scurf may be easily and expeditiously removed from the carcasses of hogs during the cleaning process. Further objects of my device are to assure the proper cleaning and removal of hair and scurf from the carcasses of hogs and doing away with the necessity of further cleaning of carcasses by means of knife or scraper. Further merits of the device consist in that it facilitates the removal of hair and scurf from the wrinkles and depressions in the skin of the carcasses and which has not been accomplished by any other method or device previously used.

The invention consists of parts made and combined as hereinafter fully described and set forth in the claim.

In the accompanying drawings Fig. 1 is a face elevation of the device. Fig. 2 is a vertical section of the device on line 2—2 of Fig. 1.

The device consists in the use of steel wire cables of various sizes, each cable consisting of numerous small wires. Sections of such cables are attached to rubber belting with the ends of such cables projecting beyond the end of belting. The cleaning of carcasses is accomplished with this device by the rotary movement of the machine used for the removal of hair and scurf from hog car-

casses by bringing the ends of the cable in contact with the carcasses while passing through the machine. The length and size of the cables varies according to the distance of the shaft from the hog carcass, and the portion of the carcass to be cleaned. The size and number of cables may be varied according to necessity.

In the drawings, A represents a section of belting made from alternate layers of cotton fibre coated with rubber, forming a section of a belt, the length of said belting to be determined by necessity or distance of hog carcass from the shaft to which belting is attached.

B represents a section of steel spring wire cable varying in length as necessity requires depending on the distance from the shaft to the hog carcass. This special quality of wire has been used to advantage in the cleaning of hogs' heads.

C represents a metal plate containing a number of openings through which bolts are inserted to hold sections of steel cable to rubber belting.

D represents holes through metal plate C. E represents holes through rubber belting A, through which bolts may be passed in order to fasten the device to the rotatable arms of the hog cleaning apparatus.

F represents steel spring wire cables attached to section of rubber belting as in A. These sections of cable are being used for cleaning certain portions of hog carcasses such as the shackle feet or other portions of carcasses.

H represents section of steel spring wire cable as shown by B and F.

J represents bolt used for purpose of bolting B, F and H to A.

K represents metal plate used on the opposite side of rubber belting from steel cables to prevent mutilation of rubber belting by nut L.

L represents metal nut engaging bolt J.

M represents section of spring steel wire cable as used when attached directly to metal shaft in hog dehairing machine, and may be used in varying lengths depending on the distance of the hog carcass from the revolving shafts.

From the foregoing, it is thought that the construction, operation, and advantages of

successfully cleaning and removing hair and scurf from hog carcasses will be apparent to operators of hog slaughtering establishments without further description, and it will be understood that various changes in size, shape, proportion, and minor details of construction may be resorted to without departing from the spirit or sacrificing any of the advantages of the invention.

10 I claim:

An attachment for a hog cleaning ma-

chine, comprising a section of rubber belting, sections of steel wire cables, a metal plate, bolts passing through said plate, between the sections of steel wire cables and 15 the rubber belting for holding said cables in fixed position on said rubber belting, the ends of said cables extending beyond the outer end of said belting, and means for fastening said belting to the rotatable arms 20 of the hog cleaning machine.

ROBERT B. LEEPER.
